United States Patent

Des. 237,729
Patented Nov. 18, 1975

237,729

TERRARIUM

Ciro C. Coppa, 315 W. 6th St.,
San Pedro, Calif. 90731

Filed Oct. 11, 1974, Ser. No. 514,191

Term of patent 14 years

Int. Cl. D11—02; D30—02
U.S. Cl. D35—3 A

Fig. 1.

Fig. 2.

Fig. 3.

Fig. 4.

Fig. 5.

FIG. 1 is a front perspective view of the terrarium showing my new design;

FIG. 2 is a top plan view of FIG. 1;

FIG. 3 is a left side elevation view with the undisclosed right side elevation view being the same in appearance as the left side view shown;

FIG. 4 is a front elevation view of FIG. 1 with the undisclosed rear elevation view being the same in appearance as the front view shown;

FIG. 5 is a bottom plan view of FIG. 1;

FIG. 6 is a front perspective view of a second embodiment of the terrarium showing my new design;

FIG. 7 is a left elevation view of FIG. 6 with the undisclosed right side being the same in appearance as the left side shown;

FIG. 8 is a top plan view of FIG. 6;

FIG. 9 is a front elevation view of FIG. 6 with the undisclosed rear view being the same in appearance as the front view shown; and

FIG. 10 is a bottom plan view of FIG. 6.

I claim:

The ornamental design for a terrarium, substantially as shown and described.
